WELL DRILLING SYSTEM

**Nathan Wilkinson, Wauwatosa, Wis., assignor to
Allis-Chalmers Manufacturing Company, Mil-
waukee, Wis., a corporation of Delaware**

**Application June 29, 1933, Serial No. 678,235
Renewed February 13, 1935**

22 Claims. (Cl. 255—19)

This invention is in part a continuation of the application of Nathan Wilkinson, Serial No. 512,899, filed February 2, 1931, for a Power transmission system. No claim is made herein to the system of motor and generator control of general application herein disclosed inasmuch as claims of such character appear in the above identified application and in application Serial No. 10,155, filed March 9, 1935, which is a division 5 of the present application.

This invention relates to power transmission systems and control therefor. It may be used in connection with the operation of a power driven tool and more particularly in connection with apparatus for drilling holes. It is especially adapted for use with rotary oil well drilling rigs.

10 A large number of different operating conditions are encountered in the drilling of oil wells. It is accordingly an object of the invention to provide a power transmission system which is flexible, enabling it to meet the varied operating conditions. A more specific object is the attainment of such flexibility with a minimum of cost; and also with a maximum of reliability.

2.5 A further object is the provision of an electric power transmission system in which internal combustion engines are used as prime movers, and further, in which close regulation of engine speed is not required. A more specific object is
3.0 the provision of such a system in which two engines are used each one automatically carrying its proportion of the total load.

In connection with oil well drilling apparatus of the type in which water is pumped into the drill hole, it is an object to provide a system of power transmission in which either the pump motor or the drill motor may be started, stopped and otherwise controlled, without affecting the other motor.

40 Still another object is the provision of a power transmission system in which all of the drilling and pumping operations and all of the ordinary and usual hoisting operations may be performed with either one prime mover in operation, or
43 more than one.

Still another object is the provision of a well drilling system in which one or more of a plurality of electric motors are used to selectively drive the hoisting, pumping, and drilling mechanism, the energy for the motors being selectively furnished by one or more of a plurality of engine driven generators which are preferably of different capacities.

A further object of the invention is the provision of a well drilling system in which one or

more of a plurality of electric motors are used to selectively drive the hoisting, pumping, and drilling mechanism, the energy for the motors being supplied during certain operations from all of a plurality of engine driven generators which are connected in series-parallel and supplied during other operations from parallel connected pairs of the generators.

A further object is to provide a well drilling system of the above character with a plurality of engine driven generators each having a rheostat for controlling the excitation of the field winding thereof, and more specifically the provision of clutch devices for rendering all of said rheostats simultaneously operable during certain operations and for rendering said rheostats operable in pairs during other operations. 10 15

Other objects will appear hereinafter as the description of the invention proceeds.

The novel features of the invention will appear from this specification and the accompanying drawings showing one embodiment of the invention and all these novel features are intended to be pointed out in the claims. 20

In the drawings:

Fig. 1 is a diagrammatic showing of one embodiment of the invention with particular relation to the electrical control features thereof.

Fig. 2 is a more or less diagrammatic elevation of mechanical features of one type of oil well drilling rig in connection with which the invention may be used. 30

Figs. 3 to 7 inclusive are diagrams of various electrical power connections which may be obtained with the system shown in Fig. 1. 35

Fig. 8 is a diagrammatic showing of an improved embodiment of the invention with particular relation to the electrical control features thereof.

Figs. 9 to 13 are schematic diagrams showing 40 various electrical power connections which may be obtained with the system shown in Fig. 8.

Referring to Fig. 1 of the drawings a prime mover 1 is here shown as connected to a pair of generators 2, 3. The generator 2 is diagrammatically indicated as of larger capacity than the generator 3. Another prime mover 4 is here shown as connected to two generators 5, 6 of which 5 is indicated as the larger. The generator 2 has its terminals connected respectively to conductors 7 and 8 while the generator 3 has its terminals connected respectively to conductors 9 and 10. The embodiment of the system here shown includes a pair of intermediate conductors 11, 12. The conductor 11 is connectable

5 to the conductor 7 by means of a contactor 13, and is also connectable to the conductor 8 by means of a contactor 14. The conductor 12 is connectable to the conductor 8 by means of a contactor 15, and is also connectable to the conductor 10 by means of a contactor 16.

10 Where two sets of engines and generators are utilized as in the illustrative embodiment, the generator 5 may have one of its terminals connected to conductor 8 and the other terminal may be connected to a conductor 17. The generator 6 may have one of its terminals connected to conductor 10 and the other to the conductor 17.

15 It will be evident as the description proceeds that more than two sets of engines and generators may be utilized. Where two or more sets of generators are used, the generators of like capacity may be used in series.

20 A pair of conductors 18, 19 is provided which are connected respectively to the blades of switches 20, 21 which are both of the single pole double throw type. The switch 20 is adapted to connect the conductor 18 to either the conductor 7 or the conductor 8. The switch 21 is adapted to connect the conductor 19 to either the conductor 8 or the conductor 17.

25 The conductor 18 is connected, through a time element overload relay coil 22, to a bus 23, whereas the conductor 19 is connectable through a contactor 24 to a bus 25. One or more motors may be connected to the buses 23, 25, two motors 26, 28 being here shown. The motor 26 is connectable to buses 23, 25 by a switch 27, operating in unison with which is an auxiliary contact 53 for a purpose which will appear hereinafter. The motor 28 is connectable to the buses 23, 25 by a switch 29 which also includes an auxiliary switch 50.

30 Another motor 30 is here shown as having its terminals connected to the blades of a pair of single pole double throw switches 31, 32 respectively. The switch 31 is adapted to connect one terminal of motor 30 to either the conductor 11 or the conductor 12. The switch 32 is adapted to connect the other terminal of motor 30 to either conductor 12 or to conductor 17. Interposed in one of the conductors leading from one of the terminals of motor 30 is the coil of a time element overload relay 59 which is in a circuit to be described hereinafter.

35 An exciter 33 is here shown as connectable to the buses 34, 35 which serve to feed the operating coils of the various contactors and the field windings of the generators and motors as will be described in detail.

40 The field windings 41, 44 of the generators 2 and 5 respectively are here shown as controllable by a pair of reversible potentiometer rheostats 37, 38 respectively. One set of terminals of the potentiometer rheostats 37, 38 are connected by means of a conductor 39 through the contacts of the overload relay 22, to the bus 34. The other set of terminals of the rheostats 37, 38 are connected to the bus 35. The movable contacts of rheostat 37 are connected by means of conductors 40, 41 to the terminals of field winding 41, which latter is here shown as shunted by a resistance or rheostat of any desired form. The 45 movable terminals of rheostat 38 are connected by means of conductors 42, 43 to the terminals of field winding 44, which is also here shown as shunted by a resistance or rheostat. For many of the conditions of operation the movable members of rheostats 37 and 38 may be operated in

5 unison but if it is desired to operate these rheostats separately a coupling 111 may be disengaged. Operable in unison with rheostat 38, and of course with rheostat 37, is shown a contact 45 cooperable with a ring contact 46. The contact 45 is connected to the bus 35. The ring contact 46 has a gap 47 therein in such position that when the rheostats 37, 38 are in the "off" position the contact 45 does not engage the ring 46. For the sake of simplicity only one ring 46 and contact 45 10 have been shown but if desired there may be one such ring and contact not only for rheostat 38 but also for rheostat 37, this being a mere duplication of parts.

15 The ring 46 is connectable through conductors 15 48, 49 and the auxiliary switch 50 to one terminal of a field winding 51 for the motor 28. The other terminal of the field winding 51 is connected to bus 34. The ring 46 is also connectable through a conductor 52 and the auxiliary switch 53 to a field winding 54 of the motor 26, the other terminal of said field winding being connected to bus 34. The conductor 48 is connected by a conductor 109 to a contact 83 with which latter blade 81 of switch C is cooperable. 25

20 The field windings 64 and 61 of generators 3 and 6 respectively are also here shown as controllable by reversible potentiometer rheostats 57 and 58 respectively. One set of terminals of the resistances of the rheostats 57, 58 are connectable 30 by means of a conductor 55 to the bus 34. The other set of terminals of said resistances is connected to bus 35. Interposed in the conductor 55 are the contacts of the overload relay 59 and the contacts of a relay 66. The movable contacts of rheostat 57 are connected by conductors 59, 60 to the terminals of field winding 61, and the movable contacts of rheostat 58 are connected by conductors 62, 63 to the terminals of field winding 64. Said field windings may be shunted by resistances 40 as shown. Similarly as described in connection with rheostats 37 and 38, there is here shown one contact ring 66 with which a contact 65 operable in unison with rheostat 58 cooperates. The ring 66 also has a gap 67 so that when the rheostat 58 45 (or the rheostat 57) is in the "off" position, the contact 65 will be out of engagement with the contact 66. A coupling 112 may also be provided between the rheostats 57 and 58 for reasons as stated in connection with rheostats 37 and 38. 50 The ring 66 is connected through a conductor 110 to a contact 84 of a master control switch C. The contact 65 is connected to the bus 35.

55 Cooperable with contact 84 is a switch blade 81 of master switch C, which blade is connected by 55 means of a conductor 68 to one terminal of a field winding 70 for the motor 26. The other terminal of said field winding is connected to the bus 34, and said field winding may also be shunted by a resistance as shown. 60

65 The operating coil for contactor 56 has one terminal connected to conductor 55 and the other terminal connected through a contact 71 to the bus 35. The contact 71 is controlled by means of a lever 99 which will be further described hereinafter in connection with Fig. 2.

70 The operating coils of contactors 13 and 15 are here shown as in parallel and interposed in a conductor 72 one end of which is connected to bus 34 and the other end of which is connected to a contact 73 of the master control switch C. A blade 74 of the switch C is connected to bus 35, and is cooperable with contact 73.

75 The operating coils of contactors 14 and 16 are here shown as in parallel and interposed in a 75

conductor 75 one terminal of which is connected to bus 34 and the other terminal of which is connected to a contact 76 of the switch C. The blade 74 of the switch C is also cooperable with the contact 76.

The operating coil of contactor 24 is interposed in a conductor 79 one terminal of which is connected to bus 34 and the other of which is connected to a contact 78 of the switch C. Cooperable with contact 78 is a blade 77 of the master switch C. The blade 77 is also electrically connected by conductor 80 with the blade 74, and therefore also to bus 35.

For a purpose which will appear in connection with the description of the operation of the system, a switch 85 is provided for bypassing the contactor 24. The switch is, under the usual operating conditions, open.

Referring now to Fig. 2, this shows in more or less diagrammatic form an oil well drilling rig of the rotary type with which the invention may be utilized. It is to be understood that the particular form of mechanical drilling rig is shown only by way of illustration so that one way in which applicant's invention may be utilized may be better understood. The drilling rig here shown comprises a hollow drill 86 around which is disposed a casing 87 which is sunk around the drill as the drilling proceeds. The drill 86 may be rotated in any suitable manner by means of a gear 88 driven by a bevel pinion 89 from a shaft 90. The shaft 90 may be connected to a driving chain 92 by means of a clutch 91 operable by a lever 95. The driving chain 92 is in operative relation to a shaft 93 which is in turn driven by a driving chain 94 from the motor 30 which corresponds to the motor 30 in Fig. 1. A shaft 96 is provided which carries fast thereon a winding drum 97. The shaft 96 may be connected to a driving chain 100 by means of a clutch 98 operable by a clutch lever 99. The clutch lever 99 is operatively related to the switch 71 which corresponds to the switch of same number in Fig. 1, and it will be apparent that when the clutch 98 is disengaged the switch 71 is closed. A brake 101 is provided for the drum 97, which brake is operable by means of a brake lever 102.

The winding drum 97 is adapted to receive a cable 103 which runs to the top of a derrick 104 and is passed over suitable pulley blocks or sheaves at the top of the derrick and also over a sheave operatively related to the drill rod 86, so that the winding drum 97 may be used to hoist and lower the drill rod 86, or other desired parts. The drill rod is here shown as connected by means of a flexible hose 105 to a pipe 106, in turn connected to a pair of pumps 107, 108 of any suitable form. The pumps are here shown as driven respectively by the motors 26, 28 which correspond to those of the same number in Fig. 1.

The operation of the system will be best understood by a consideration of various power set-ups that may be secured therewith.

If it is desired to hoist the drill rod 86, or any other part attached to the hoisting cable 103, at full speed, the motor 30 is connected to the large generators 2, 5 in series, as indicated in Fig. 3, as follows: It is assumed that the exciter 33 is connected to the buses 34, 35, and that the hoisting drum 97 is connected to the shaft 93 by means of the clutch 98. The switch 31 is thrown to its upper contact and the switch 32 to its lower contact. The master switch C is thrown to the left, as viewed in the drawings, thereby connecting the blades 74 and 81 to the contacts 73 and 83 re-

spectively. It will be noted, incidentally, that the contact with which the blade 77 contacts, in this position, is, in the illustrative embodiment, a dead contact. With the master switch C in the position stated the contactors 13 and 15 have their operating coils energized and are closed. It may be noted that in the illustrative embodiment and in the particular set-up now under consideration the contactor 15 will not be in any circuit. It will be also noted that while the blade 81 is in engagement with the contact 83 the field winding circuit for the motor 30 is not as yet completed since the contact 45 is, in the starting position, not in contact with the ring 46. The generator field winding rheostats 37, 38 may now be operated to increase the electromotive force generated by generators 2 and 5, also thereby closing the field winding circuit for motor 30. It is of course clear that the motor 30 will operate in a direction dependent upon which direction the rheostats 37 and 38 have been moved. The provision of differential series field windings 113, 114 for generators 2, 5 respectively, gives these machines drooping characteristics, which coacts with the method of speed control of motors 30, 25 26 and 28 by generator field excitation to give good starting torque and acceleration control.

With the set-up of Fig. 3 described above the motor 30 which may be say a 400 H. P. motor operating at 1000 R. P. M. at 350 volts with a 30 peak load of say 600 H. P., is fed from the two large generators which are say of 200 k. w. capacity each operating at 1200 R. P. M. and generating 175 volts each. The engines 1, 4 are rated at 385 H. P. each at 1200 R. P. M. The foregoing figures are given merely by way of example as are also the ratings of other machines to be hereinafter noted. It will be obvious that the invention is in no way limited to the selection or use of machines of the ratings, voltages and speeds herein given and that those skilled in the art may easily make a choice of ratings etc. suitable to meet any particular conditions. The ratings given in this specification are cited merely to further bring out the possibilities and flexibility of the disclosed system.

The engines 1 and 4 are provided with the usual governors (not shown) so that if desired the speeds of these engines may be kept at substantially 1200 R. P. M., as in the above cited example, or at any other selected speed, as will be understood by those skilled in the art.

If it is desired to hoist at half speed the electrical set-up of Fig. 4 may be secured by throwing both the switches 31 and 32 to their upper positions. The mechanical set-up of the parts of Fig. 2 are the same as described in connection with the set-up of Fig. 3, and the master switch is also in the same position. It will be noted, however, that since in the set-up of Fig. 4 the motor 30 is operating from generator 2 only, that the contactor 15 is now in the circuit feeding motor 30. With this set-up the engine 1 is the only one in operation and may operate as before with 385 H. P. at 1200 R. P. M. The 200 k. w. generator 2 now feeds the motor 30 at 175 volts and therefore the motor runs at half speed, that is, 500 R. P. M.

If for any reason it is desired to hoist at half speed with the motor 30 fed from generator 5, the electrical set-up will be the same as in Fig. 4, but to secure the same the switches 31 and 32 are both thrown onto their lower contacts. The contactor 15 is here again in circuit with the motor 30, and of course the master switch C remains

in the same position as for the set-up in Figs. 3 and 4.

It will be noted that with the hoisting set-ups as hereinbefore described in which the lever 99 has been thrown to cause engagement of the clutch 98, the switch 71 is opened, thereby de-energizing the contactor 56. The opening of this contactor opens the circuit of rheostats 57 and 58 and prevents current from being fed to the field windings of generators 3 and 6.

If it is desired to rotate the drill 86 and pump water down through the drill at the same time, the clutch 98 is thrown out (thereby closing switch 71) and the clutch 91 is thrown in so as to connect the driving shaft 90 for rotating the drill, to the shaft 93. The switch 31 is thrown to its upper position and the switch 32 is thrown to its lower position. The switches 20 and 21 are thrown respectively to their upper and lower positions. The master switch C is thrown to its right hand position, thereby energizing the operating coils of contactors 14 and 16, by reason of the engagement of blade 74 with contact 76. It will be incidentally noted that contactor 16 will not be in any circuit in this particular set-up. The engagement of blade 77 with contact 78 energizes the operating coil of contactor 24. If it is desired to use both pumps 107 and 108, both switches 27 and 29 are closed thereby connecting the armature circuits of motors 26 and 28 to the conductors 7 and 17. While the auxiliary switches 53 and 58 are closed it will be noted that the circuits for the field windings 54 and 51 are incomplete since at the start contact 45 is not in engagement with ring 46. The rheostats 37 and 38 may now be operated in the proper direction thereby causing the generators 2 and 5, in series, to feed the pump motors 26, 28 as shown in Fig. 5. Inasmuch as the contact 71 is closed, the relay 56 is energized and therefore operation of the rheostats 57, 58 will supply current to the field windings of generators 3 and 6. The engagement of contact 68 with ring 66 causes the field winding 70 of motor 30 to be supplied with current.

It will be evident that with the set-up of Fig. 5 the motor 30 may be used at full speed for the drilling operation since it is fed from the generators 3 and 6 in series. By way of example, the generators 3 and 6 may be of 40 k. w. capacity each at a voltage of 125. For this drilling and pumping operation the engines 1 and 4 may have their governors set to operate at say 850 R. P. M., the engines producing at that speed say 260 H. P. The motor 30 may then operate at say 710 R. P. M. at 250 volts and produce say 100 H. P. The larger generators 2 and 5 operating at 850 R. P. M. at 125 volts may produce say 142 k. w. Each of the pump motors 26, 28 may be rated at say 276 H. P. at 850 R. P. M., noting that adequate pumping capacity may be obtained by using either one of the pumping units; however, from the above data it is apparent that there is adequate generator capacity for the other pumping unit to be operated at the same time with reduced output for "mixing mud", if desired. It will be obvious of course that with the machines in the cited example, the power produced and consumed may be widely varied by adjustment of the rheostats 37, 38 and 57, 58.

If the operator should for any reason, while the system is operating with the set-up of Fig. 5 as hereinbefore described, attempt to use the hoist drum 97 by throwing the clutch 98 into engagement, the contact 71 will be opened thereby

deenergizing contactor 56 and consequently de-energizing the field circuits of the generators 3 and 6, to which the motor 30 is at that time connected.

If it is desired to drill and pump at half speed, the set-up of Fig. 6 may be secured as follows: The mechanical set-up in connection with Fig. 6 may be the same as in connection with Fig. 5. The switches 31 and 32 are both thrown to their upper positions, and the switches 20 and 21 are likewise both thrown to their upper positions. The master switch C remains in its right hand position as described in connection with the set-up of Fig. 5. By operation of the rheostat 58 the motor 30 may now be fed from generator 3 through contactors 14 and 16 while either of the motors 26, 28 may be fed from generator 2. The voltage of generator 2 may of course be controlled by rheostat 37. For this set-up the engine 1 preferably has its governor set for a lower speed as in case of the half speed hoisting set-up of Fig. 4. The pump motor 26 may now operate with a rating of say 137 H. P. at 425 R. P. M. since it is fed from one generator at 125 volts. The drill operating motor 30 may produce say 50 H. P. at 355 R. P. M. being also fed at say 125 volts from generator 3.

It sometimes occurs that it is desirable to hoist and pump at the same time. For this purpose the "fishing" set-up, as shown in Fig. 7, may be obtained. With this set-up hoisting operations may be performed as in case a drill rod should break, and at the same time one of the pumps may be used. This "fishing" setup may be secured with a pump motor fed from generator 2 and the motor 30 fed from generator 5 or vice versa. The operations for securing the set-up shown in Fig. 7 will first be described. The clutch 98 is thrown in and if it is desired to hoist only, the clutch 91 is thrown out. The switches 31 and 32 are both thrown to their lower positions. The switches 20 and 21 are both thrown to their upper positions. The master switch C is thrown to its left hand position thereby causing closure of contactors 13 and 15. The switch 85 is closed by hand, in the illustrative embodiment, to thereby connect the bus 25 to the blade 21. It will be noted that with the master switch in its left hand position the bypassing of contactor 24 is necessary since in that position of the master switch the coil of contactor 24 is not energized. The switch 27 for pump motor 26 is closed and the rheostats 37 and 38 operated either separately or in unison as desired. For this set-up the engines 1 and 4 may have their governors set to cause operation of the engines at substantially 1200 R. P. M., for example. The pump motor 26 may then operate at say 590 R. P. M. with a rating of 192 H. P., being fed from the generator 2 operating with a rating of 200 k. w. at 1200 R. P. M. The motor 30 operates at a rating of say 200 H. P. at 500 R. P. M. from the generator 5 operating at a rating of 200 k. w. at 1200 R. P. M.

If for any reason it is desired to operate the motor 30 from generator 2 and a pump motor from generator 5, the switches 31 and 32 are both thrown to their upper positions and the switches 20 and 21 are both thrown to their lower positions. The master switch remains in its left hand position and the remaining operations are similar to those described in connection with Fig. 7.

If for any reason it is desirable to rotate the drill as it is being hoisted, or lowered, with for

example the "fishing" set-up of Fig. 7, the clutch 91 may be thrown into engagement.

In general, it will be apparent that current will not be supplied to either of motors 26, 28 unless the auxiliary switches 53 and 50 are closed. Moreover, when the rheostats 37, 38 and 57, 58 are in their "off" positions, the field winding circuits of the pump motors will be interrupted even if the auxiliary switches 53, 50 are closed, which is true irrespective of the position of the master switch C. When the rheostats 57, 58 only for the smaller generators 3, 6 are "on" field current can be obtained for the motor 30 only if the master switch C is in its right hand position, which is the position for the normal drilling operation. When the rheostats 37, 38 only are "on" current can be obtained for the field windings of the pump motors provided the switches for these motors are respectively closed, and current can be obtained for the field winding of motor 30 provided the master switch C is in its left hand position which is the hoisting position.

It will be obvious that if desired, particularly in connection with the set-ups of Figs. 4, 6 and 7, the rheostat for generator 2 may be operated separately from the rheostat for generator 5 by simply disengaging the coupling 111, and particularly in the case of Fig. 6 the rheostat for generator 3 may be operated separately from that for generator 6 by disengaging the coupling 112.

It will be evident from the description of the various set-ups that if desired only one engine and one set of generators need be used, if desired, for the first few thousand feet of drilling (the set being say as in Fig. 6) and that subsequently, or at any desired time, more than one engine and set of generators may be used for drilling (the set-up being say as in Fig. 5). It is of course obvious that the same applies at any stage of the drilling since if one engine fails, operations may be carried on with the other engine but with the driving motors operating at half speed. Full torque is however available whether the motors are running at full speed or half speed. Moreover to secure this full torque under either condition of operation it is unnecessary to alter the driving or gear ratio as between the driving motors and the mechanical drill rigging.

What has been stated above also applies with regard to the full speed and half speed hoisting set-ups of Figs. 3 and 4 respectively.

The exciter 33 being separately driven by an auxiliary engine (not shown) makes possible the use of said exciter for various purposes, such as for lighting the drill site, without necessity of having the main engines 1, 4, running, or even before said main engines are available at all as while the drilling rig and drive are being erected.

Referring now to Figure 8 of the drawings a prime mover 1 is arranged to drive a pair of generators 2 and 3 which are diagrammatically indicated as of equal capacity. Another prime mover 4 is arranged to drive a pair of generators 5 and 6 which are diagrammatically indicated as of equal capacity. Generators 2 and 5 are permanently connected in series noting that the outer terminals of these generators are connected to conductors 120 and 122 and that the intermediate terminals are connected to common conductor 121. Generators 3 and 6 are permanently connected in series noting that the outer terminals of these generators are connected to conductors 123 and 124 and that the intermediate terminals are connected to common conductor 121. Gen-

erators 2 and 5 are provided with series differential field windings 113 and 114, self excited field windings 140 and 141 and separately excited field windings 41 and 44, respectively. Generators 3 and 6 are provided with differential series field windings 142 and 143, self excited field windings 144 and 145, and separately excited field windings 64 and 61, respectively. The separately excited field windings and the self excited field windings are normally cumulative. The self excited winding of each generator is so proportional that its ampere turns are always less than the air-gap ampere turns, that is, the resistance of this winding is such that the plotted curve (current in self excited winding as abscissa and terminal voltage as ordinate) never intersects the voltage characteristic curve of the generator. The polarity and magnitude of generator voltages are therefore determined by the separately excited windings. The main purpose of the self excited and the series differential field windings is to accentuate the drooping characteristic of the generators so as to prevent the stalling of a prime mover in event one prime mover is temporarily unable to develop as much torque as the other prime mover. That is, stalling of an imperfectly operating prime mover is prevented by the automatic weakening of the self excited field windings of the generators connected thereto upon occurrence of the reduction in speed of the faulty prime mover. Electromagnetic contactors 135 and 136 are provided to connect series connected generators 2 and 5 in parallel with series connected generators 3 and 6.

Pump motors 26 and 28 may be selectively connected to load conductors 23-25 by means of switches 27 and 29. An electromagnetic contactor 24 is operable to connect load conductor 25 with the blade of switch 21, noting that load conductor 23 is permanently connected to the blade 40 of switch 20 through the coil of overload relay 22. By means of hand operated switches 20 and 21 the load conductors 23 and 25 may be selectively connected either to conductors 18 and 121, or conductors 19 and 121, or to conductors 18 and 19, as hereinbefore described in connection with Figure 1.

The drilling or hoisting motor 30 may be selectively connected to conductors 125 and 121, or 126 and 121, or to conductors 125 and 126 by means of hand operated switches 31 and 32 in substantially the same manner as described in connection with Figure 1.

Separately excited field windings 41, 44, 64 and 61 are controlled by rheostats 37, 38, 58 and 57 respectively. These rheostats are all energized from bus 34-35 through conductors 150 and 151 when overload relays 22 and 69 are in their normally closed positions. An overload on either motor 30 or the pumping motor 26 or 28 will cause the respective overload relay 69 or 22 to operate to deenergize all of the separately excited generator field windings. Rheostats 37 and 38 are mechanically connected together by clutch 111 and rheostats 57 and 58 are mechanically connected together by clutch 112 in the same manner as described in connection with Figure 1. An additional clutch 152 is arranged between rheostats 38 and 57 so that all four rheostats may be simultaneously operated or, if clutches 111 and 112 are disconnected, so that rheostats 38 and 57 may be operated simultaneously. An additional clutch 153 is arranged between rheostats 37 and 58, so that with clutches 111 and 112 disconnected, rheostats 37 and 58 may be simultaneously oper-

ated. The utility of this arrangement will be better understood in connection with the description of the operation of the generators during certain operations.

5 Master controller C is a double pole, double throw switch having blades 131 and 132. When these blades are thrown to their left hand position a circuit is established from bus 35 through conductor 130, conductor 80, blade 131, conductor 133, operating coil of contactor 135, through conductor 137 to bus 34, thereby causing contactor 135 to close. Another circuit is also established from bus 35 through conductor 130, conductor 80, switch blade 132, conductor 134, operating coil of contactor 136, and through conductor 137 to bus 34. The closure of contactors 135 and 136 connect the generators in series-parallel. When the blades of the master controller C are moved to their right hand position 10 a control circuit is established from bus 35 through conductor 130, conductor 80, switch blades 131, conductors 79, the operating coil of contactor 24 to bus 34 thereby causing contactor 24 to close. Another circuit is also established from bus 35 15 through conductor 130, conductor 80, switch blade 132, conductor 134, operating coil of contactor 136, through conductor 137 to bus 34. The closure of contactors 136 and 24 connects generators 2, 5 and 3, 6 to motor 26 (or 28) and motor 10 20 respectively.

Inasmuch as motors 26, 28 and 30 are used in close proximity to explosive gases it is necessary that these motors be totally enclosed and for this reason each of these motors is provided with a 25 forced draft ventilating system. For example, motor 26 is provided with a blower motor 155 which is connected across the field winding 54 and field control rheostat 156. Pump motor 28 is provided with a blower motor 157 which is connected 30 across field winding 51 and field control rheostat 158. Motor 30 is provided with a blower motor 159 which is connected across field winding 70. It is to be noted that by connecting these 35 ventilating motors across the respective field windings of the motors to be cooled that considerable saving is obtained in the number of conductors necessary.

All of the generators of this system of Fig. 8 being of ample capacity, as distinguished from 40 the system of Fig. 1, where the generators 3, 6 are of reduced capacity as compared with the generators 2, 5, the same necessity is not present for provisions, such as the switch 71, actuated with the hoist clutch 98, for preventing operation 45 of the motor 30 for hoist-driving purposes when supplied from any particular generator or generators.

The operation of the system will be best understood by a consideration of the various mechanical set-ups and electrical circuits that may be secured with the system hereinbefore described.

If it is desired to hoist the drill rod 86 or any other part attached to the hoisting cable 103, at 45 full speed, the field rheostats should be moved to such a position that the clutches 111, 112 and 152 may be moved to their engaging positions. With the rheostats all simultaneously operable the voltages of the generators will be substantially equal which is a prerequisite to the operation of these 50 generators in parallel. The switch 31 is moved to its upper position and the switch 32 is moved to its lower position thereby connecting motor 30 to conductors 125 and 126. The master controller C may then be moved to its left hand position thereby connecting generators 2, 3, 5 and 6 55

in series-parallel as schematically shown in Figure 9. The field rheostats 37, 38, 57 and 58, are then moved in one direction or the other from their neutral position to simultaneously raise the voltage of all generators and thereby cause motor 5 30 to start and run in one direction or the other.

With the hoisting set-up shown in Figure 9 above described the motor 30 may be of 400 H. P. rating operating at 1,000 R. P. M. at 350 volts with a peak load capacity of 600 H. P. noting that since 10 each generator may, for example, be of 150 k. w. rating that 600 k. w. will be available for hoisting. The ratings of the generators and motors are merely cited to more clearly set forth the utility of the invention and are not intended to be taken 15 in a limiting sense.

If a break down occurs on one of the prime mover units hoisting at half speed may be obtained by connecting motor 30 to the parallel connected generators of the remaining unit by 20 means of switches 31 and 32 as schematically shown in Figure 10, noting that with this connection 300 k. w. of generating capacity will be available for operating motor 30 at about half speed. 25

If it is desired to rotate the drill 86 and pump liquid down through the drill at the same time; the clutch 98 of Figure 2 is disengaged and the clutch 91 is engaged so as to connect the driving shaft 90 to the shaft 93 for rotating the drill. 30 The switch 31 is moved to its upper position and the switch 32 is moved to its lower position. If it is desired to use both pumps 107 and 108, both switches 27 and 28 are closed thereby connecting motors 26 and 28 to the load conductors 23 and 35 35 25, it is to be noted, however, that adequate pumping capacity may be obtained by using either one of the pumping units; however, in some instances it is desirable to operate the other pumping unit at reduced output to mix the liquid which is 40 pumped into the casing of the well. Switches 20 and 21 are also moved to their upper and lower positions respectively to connect generators 2 and 5 to one or both of the pumping motors 26 and 28. The master switch C is moved to its right hand 45 position, thereby energizing the operating coils of contactors 136 and 24, noting that, since contactor 135 is not energized in this position, generators 2 and 5 will not be connected in parallel with generators 3 and 6. The circuit connections for 50 obtaining the above described set-up are schematically shown in Figure 11. Inasmuch as generators 2 and 5 are not electrically connected with generators 3 and 6 it is desirable that field rheostats 37 and 38 be connected together by means 55 of clutches 111 and that rheostats 57 and 58 be connected together by clutches 112, noting that for this set-up the clutches 152 and 153 should be disengaged so that the above described pairs of rheostats may be independently operable to 60 vary the speed of the pumping motors or the speed of the drilling motor 30 independently.

It will be evident that with the set-up of Figure 11 the motor 30 may be operated at full speed for the drilling operation (which usually requires 65 only about 100 H. P.), and since motor 30 is fed from generators 3 and 6 in series it is evident that one pumping unit may be operated also at full speed noting that if the other pumping unit is also used at the same time for mixing liquid it 70 needs only to operate at a fraction of its rated capacity. For the above described drilling and pumping operation the engines 1 and 4 may have their governors set to operate at say 850 R. P. M. If necessary, the full rated capacity of generators 75

3 and 6, namely, 300 k. w. may be used to energize motor 30 for drilling operations, yet such is rarely necessary. It will be obvious that the power output of the generators in the above example 5 may be widely varied to meet the requirements of the conditions by adjustment of the rheostats 31, 32 and 51, 58.

If a breakdown occurs on one of the prime mover units, the drilling and pumping operations 10 may be continued at half speed using the other prime mover unit as shown in Figure 12. The position of the clutches 91 and 98 will be the same as described in connection with Figure 11. Switches 31 and 32 are moved to connect motor 15 30 across the operative generator, whether it be 3 or 6, by means of switches 31 and 32. Likewise switches 20 and 21 are moved to connect the pump motor or pump motors across the generator which remains operative, whether it be 2 or 5. The master switch remains in its right hand position as 20 described in connection with the set-up of Figure 5. All of the rheostat clutches (111, 112, 152 and 153) are moved to disengaged position so that 25 only the rheostats associated with the operative generators may be moved from their neutral positions to separately control the voltage of the respective generators. It will thus be seen that 30 150 k. w. will be available for pumping and that 150 k. w. will be also available for drilling at slightly less than full speed by weakening the field of motor 30 by means of normally shunted resistor 160.

It sometimes occurs that it is desirable to hoist 35 and pump at the same time, noting that this condition is generally known as the "fishing" set-up. Referring now to Figure 13, with this set-up hoisting operations may be performed as in case a drill rod should break, and at the same time one of the pumps may be used. This "fishing" 40 set-up may be secured with a pump motor fed from generators 2 and 3 in parallel and the motor 30 fed from generators 5 and 6 in parallel or vice versa. Obviously, the fishing operation may be conducted with the set-up shown in Fig. 11 if 45 desired. The operations for securing the set-ups shown in Fig. 13 will first be described. The clutch 98 is engaged, and if it is desired to hoist only, the clutch 91 is disengaged. The switches 31 and 32 are both moved to their lower position 50 and switches 20 and 21 are both moved to their upper positions. The master switch is moved to its left hand position thereby causing closure of contactors 135 and 136. If it is desired to operate either one or both of pump motors 26 and 55 28 it is necessary to manually close switch 85 and one or both of switches 27 or 29. If for any reason it is desirable to rotate the drill as it is being hoisted or lowered with, for example, the "fishing" set-up of Figure 13, the clutch 91 may 60 be moved into engagement.

It is thus seen that Figure 8 is in general similar to Figure 1, however, in order to simplify Figure 8 a number of the interlocking features described in connection with Figure 1 have been 65 omitted for the sake of clearness, however, it is to be understood that these features may also be used in connection with the system disclosed in connection with Figure 8 if desired.

It should be understood that it is not desired 70 to limit the invention to the exact details of construction shown and described for obvious modifications may occur to persons skilled in the art.

It is claimed and desired to secure by Letters Patent:

75 1. In an oil well drilling rig of the type having

means for hoisting selected parts of the rig and means for operating the drill, two pairs of electric generators, the units of the respective pairs being of different capacity, a pair of prime movers for driving said pairs of generators respectively, 5 an electric motor, means for connecting said generators of larger capacity in series to said motor and for causing the latter to effect the hoisting operation at a speed independent of the speed of operation of said prime movers, 10 connecting said generators of smaller capacity in series to said motor and for causing the latter to effect the drilling operation at a speed independent of the speed of operation of said prime movers. 15

2. In an oil well drilling rig of the type having means for operating the drill, including a hollow drill rod and a pump for supplying water to said drill rod, a pair of electric generators of different capacities, a prime mover for driving said 20 generators, an electric motor for driving said pump, an electric motor for driving said drill, a second pair of electric generators of substantially the same capacities as the generators of said first pair, respectively, a prime mover for 25 driving said second pair of generators, a source of separate field excitation for said generators, means for connecting said pump motor to either or both of the generators of larger capacity and for causing operation of said pump motor at a 30 speed independent of the speed of operation of said prime movers, and means for connecting the drill driving motor to either or both of the generators of smaller capacity and for causing operation of said drill driving motor at a speed independent of the speed of operation of 35 said prime movers.

3. In an oil well drilling rig of the type having means for operating the drill including a hollow drill rod and a pump for supplying water to 40 said drill rod, two pairs of electric generators, the units of the respective pairs being of different capacity, a pair of prime movers for driving said pairs of generators respectively, an electric motor for driving said pump, an electric motor for 45 driving said drill, means for connecting said generators of larger capacity in series to said pump motor, means for connecting said generators of smaller capacity in series to said drill driving motor, and means for causing said pump and drill 50 driving motors to operate at a variable speed independent of the speed of operation of said prime movers.

4. A well drilling rig comprising means for hoisting selected parts of the rig, means for drilling, an electric motor, mechanism operable to selectively connect said electric motor either with said hoisting means or with said drilling means, a pair of electric generators of different capacities, prime mover means arranged to drive said 60 generators, and means for connecting said motor to the generator of larger capacity when said hoisting means is operable and to the generator of smaller capacity when said drilling means is operable, and for permitting variation of the speed of said motor in its hoist and drill driving operations independently of the speed of operation of said prime mover means.

5. A well drilling rig comprising means for hoisting selected parts of the rig, drilling means, 70 an electric motor, mechanism operable to selectively connect said motor to said hoisting means or to said drilling means, a pair of D. C. generators of predetermined capacity, a pair of D. C. generators of smaller capacity, a 75

pair of independent prime movers, each of said prime movers arranged to drive a generator of predetermined capacity and a generator of smaller capacity, and switching means for connecting said generators of predetermined capacity in series to said motor when said motor is operatively connected to said hoisting means and for connecting said generators of smaller capacity in series to said motor and insuring effective operation of said latter motor supplied by the generators of smaller capacity only when said latter motor is out of driving relation to said hoisting means.

6. A well drilling rig comprising means for hoisting selected parts of the rig, drill rod rotating means, an electric motor, mechanism operable to selectively connect said motor in driving relation either with said hoisting means or said drill rotating means or with both of said means, a pair 10 of electric generators of predetermined capacity, a pair of electric generators of smaller capacity, prime movers arranged to drive said generators, switching means selectively operable to connect said motor across one or both of said generators 15 of predetermined capacity or across one or both of said generators of smaller capacity, and means for rendering said motor effective for driving purposes when supplied by one or both of said generators of smaller capacity only in case said 20 hoisting means is disconnected from said motor.

7. A well drilling rig comprising a drill, means for hoisting selected parts of the rig, means for rotating the drill, an electric motor, means for drivingly connecting said motor to said hoisting 25 means or said drill rotating means, a pump arranged to circulate liquid, a second electric motor for driving said pump, a plurality of electric generators, a plurality of prime movers, an independently driven source of separate excitation 30 for said generators, means operable to connect one of said generators to supply energy to said first mentioned motor and to connect another of said generators to supply energy to said second mentioned motor, and operating connections for 35 insuring selectively that one prime mover may drive one of said generators to supply energy to one of said motors and another of said prime movers may drive another of said generators to supply energy to another of said motors, or that 40 one engine may simultaneously drive one generator to supply said hoisting and drilling motor and another generator to supply said pump motor, and means operative to control the energy supplied by said generators to said motors to insure 45 operation of said motors at speeds independent of the speed of operation of said prime movers.

8. A well drilling rig comprising a drill, means for rotating and hoisting the drill, an electric motor, means for drivingly connecting said motor to said drill actuating means, a pump arranged to circulate liquid, a second electric motor for driving said pump, a plurality of electric generators, a plurality of prime movers, means operable to connect one of said generators in energy-supplying relation to said drill-actuating motor 50 and to connect another of said generators in energy-supplying relation to said pump motor, and operating connections for insuring selectively that one prime mover may drive one of said generators to supply energy to said drill-actuating motor and another of said prime movers may drive another of said generators to supply energy to said pump motor, or that either engine may simultaneously drive one generator to supply said 55 drill-actuating motor and another generator to

supply said pump motor, and means operative to control the energy supplied by said generators to said motors to insure operation of said motors at speeds independent of the speed of operation of said prime movers.

9. A well drilling rig comprising means for hoisting selected parts of said rig, drilling means, a pump arranged to circulate liquid in the casing of said well, an electric motor arranged to drive said pump, a second electric motor, mechanism 10 operable to selectively connect said second motor in driving relation with said hoisting means or said drilling means or with both of said means, a pair of series connected electric generators, another pair of series connected electric generators, 15 two engines each serving as a common driving means for a generator of each of said pairs and means selectively operable to either connect both pairs of said generators in series-parallel to said second motor, for hoisting, or to connect said first mentioned generators in series to said pump driving motor and to connect said another pair of generators in series to said second motor for drilling and to provide for the operation of either motor at different speeds independent of 20 the speed of operation of said engines.

10. A well drilling rig comprising means for hoisting selected parts of said rig, drilling means, a pump arranged to circulate liquid in the casing of said well, an electric motor arranged to drive 25 said pump, a second electric motor, mechanism operable to selectively connect said second motor in driving relation with said hoisting means or said drilling means or with both of said means, a pair of electric generators connectable in series, 30 a second pair of electric generators connectable in series, a pair of internal combustion engines each arranged to drive one of said generators of each of said pairs, and means selectively operable either to connect said two pairs of generators in series-parallel and to connect said second motor to the aforesaid series-parallel connected generators for hoisting or to connect said generators of one of said pairs in series to said pump driving motor to circulate liquid in said casing and 35 to connect said generators of the other of said pairs in series to said second motor for drilling and to render said motors operative at different speeds independent of the speed of operation of said engines.

11. A well drilling rig comprising means for hoisting selected parts of the rig, an electric motor arranged to drive said hoisting means, a pair of electric generators connectable in series, another pair of electric generators connectable in series a pair of prime movers each arranged to drive one of said first mentioned generators and one of said last mentioned generators, and means selectively operable to connect both pairs of said generators in series parallel to said motor for 40 hoisting at full speed or to connect the generators driven by either one of said prime movers in parallel to said motor for hoisting at half speed and to render said motor operative at different speeds independent of the speed of operation of 45 said prime movers.

12. A well drilling rig comprising a drill, means for hoisting and rotating said drill, an electric motor arranged to drive said hoisting and rotating means, a pair of electric generators connectable in 50 series, another pair of electric generators connectable in series, said generators having their main field windings excited from a separate source of energy, a pair of independent internal combustion engines each arranged to drive one of said 55

first mentioned generators and one of said second mentioned generators, and means comprising selectively operable switches for connecting the generators driven by said engines in series-parallel and to connect said motor to the aforesaid series-parallel connected generators for hoisting or for connecting either one or both of the generators of one of said pairs to said motor, and for rendering said motor operative at speeds independent of the speed of operation of said engines.

13. A well drilling rig comprising means for hoisting selected parts of the rig, an electric motor arranged to drive said hoisting means, a pump arranged to circulate liquid in the well, an electric motor arranged to drive said pump, each of said motors having a separately excited field winding, motor driven ventilating blowers arranged to circulate air through said hoisting and pumping motors, the motors of said blowers being connected across said separately excited field windings respectively, a pair of engine driven electric generators, and means operable to selectively connect said hoisting and pumping motors to said generators respectively and to render said motors operative at speeds independent of the speed of operation of said engine driven generators.

14. A well drilling rig comprising means for hoisting selected parts of the rig, an electric motor arranged to drive said hoisting means, a pump arranged to circulate liquid in the well, an electric motor arranged to drive said pump, a pair of electric generators connectable in series, a second pair of electric generators connectable in series, each of said generators having a separately excited field winding and individual rheostats arranged to control the excitation of said windings, prime movers arranged to drive said generators, switching means operable to selectively connect said pairs of generators in series-parallel to said first mentioned motor for hoisting or to connect two of said generators in parallel to said hoisting motor and the other two of said generators in parallel to said pumping motor for circulating liquid in said well, and means for either connecting all of said rheostats together so as to be operable simultaneously while said switching means connect all said generators in series-parallel for hoisting or connecting said rheostats in pairs so that each pair is operable simultaneously and independently while said switching means connect two of said generators in parallel to said hoisting motor and connect the other two of said generators in parallel to said pumping motor said motors being operative at speeds independent of the speed of operation of said prime movers through suitable adjustment of said individual rheostats.

15. A well drilling rig comprising means for hoisting selected parts of the rig, means for drilling, an electric motor, mechanism operable to selectively connect said motor either with said hoisting means or said drilling means, a pair of electric generators of different capacities, prime mover means arranged to drive said generators, and means for connecting said motor to the generator of larger capacity when said hoisting means is operable and to the generator of smaller capacity when said drilling means is operable, said generator of smaller capacity being operative to cause said motor to effectively drive said drilling means only when said motor is disconnected from said hoisting means.

16. In a well drilling rig of the type having

means for imparting linear movement to selected parts of the rig and means for imparting rotative movement to one of said parts, two pairs of electric generators, a pair of prime movers for driving said pairs of generators respectively, an electric motor, means for connecting a generator of each of said pairs in series to said motor and rendering said motor operative to effect said linear movement, means for connecting the other generator of each of said pairs in series to said motor and rendering said motor operative to effect said rotative movement, and means for providing that said motor when operative to effect said linear and rotative movements may operate at different speeds independent of the speed of operation of said prime movers.

17. In a well drilling rig, an operating element capable of both rotative and linear movements, a pair of electric generators of different capacities, a prime mover for driving said generators, a second pair of electric generators of different capacities, a prime mover for driving said second pair of generators, an electric motor operable selectively to impart rotative or linear movement to said element, means for connecting said motor to one or both of said generators of larger capacity and rendering said motor operative at a speed independent of the speed of the prime mover or prime movers driving the generator or generators supplying said motor to effect linear movement of said element, means for connecting said motor to one or both of said generators of smaller capacity and rendering said motor operative at a speed independent of the prime mover or prime movers driving said generator or generators supplying said motor to effect rotative movement of said element, and means for preventing effective operation of said motor supplied from said generators of smaller capacity when said motor is connected to impart reciprocating movement to said element.

18. A well drilling rig comprising a drill, means for operating said drill to impart linear and rotative movements thereto, a pump for supplying liquid to said drill, a plurality of prime movers, means for converting the power of said prime movers and utilizing the converted power for driving said drill-actuating means and said pump, said converting means comprising a plurality of separately excited electrical generators arranged to be driven by said prime movers, an independently driven source of separate excitation for said generators, an electrical motor arranged to drive said drill-actuating means, an electrical motor arranged to drive said pump, and means for providing for the operation of said drill-actuating motor through energy supplied by a plurality of said generators driven by one or more of said prime movers or the operation of each of said motors through energy supplied by an individual generator while both said generators are driven by either one of said prime movers, and for varying the speed of operation of each said motor independent of the speed of the other said motor and the speed of the prime mover or prime movers driving the generator or generators supplying energy to said motor.

19. A power plant for drill rigs of the type including a drilling element adapted to be rotated and hoisted, comprising a plurality of engines, electro-mechanical means for converting the power of said engines and utilizing the converted power for driving said drilling means, said converting means comprising a pair of electrical generators arranged in driven relation to each

- of said engines, and an electric motor arranged in driving relation to said drilling element and operable by power supplied by one or both of the generators driven by each engine or by a generator driven by one engine connected to a generator driven by another engine, and control means for providing variation in the speed of operation of said drilling element by said motor independently of the speed of said engines
- 10 through adjustment either individually or collectively of the voltages of a plurality of said generators connected in supply relation to said motor.
20. A well drilling rig comprising a drill, means
- 15 for hoisting and rotating said drill, an electric motor arranged to drive said hoisting and rotating means, a pump arranged to supply liquid to said drill, an electric motor arranged to drive said pump, a pair of electric generators connect-
- 20 able in series, another pair of electric generators connectable in series, a pair of independent internal combustion engines each arranged to drive one of said first mentioned pair of generators and one of said second mentioned pair of generators,
- 25 and means comprising selectively operable switches for connecting the generators driven by said engines in series-parallel and to connect said hoist driving motor to the aforesaid series-parallel connected generators for hoisting or for
- 30 connecting either generator of one of said pairs of generators to said drill driving motor and either generator of the other pair of generators to said pump motor to thereby insure operation of both of said motors supplied by the generators
- 35 driven by either engine, and means for rendering said motors operative at different speeds

independent of the speed of operation of said engines.

21. In an oil well drilling rig of the type having means for operating the drill including a hollow drill rod and a pump for supplying water to said drill rod, a pair of electric generators of different capacities, means for driving said generators, an independently driven source of separate field excitation for said generators, an electric motor for driving said pump, an electric motor for actuating said drill, means for connecting said pump motor to the generator of larger capacity and for connecting the drill motor to the generator of smaller capacity and for providing for operation of each of said motors at different speeds independent of the speed of operation of the other motor and of the generator driving means.

22. A well drilling rig comprising a drill rod, means for actuating said drill rod to effect hoisting and rotation thereof, an electric motor for actuating said latter means, a pump arranged to circulate liquid in the well, a second electric motor arranged to drive said pump, a pair of electric generators, a prime mover arranged to drive both of said generators, an independently driven source of separate excitation for said generators, and means for connecting one of said generators to said drill-actuating motor and the other generator to said pump motor and for providing for operation of each of said motors at different speeds independent of the speed of the other motor and said generator driving means through variation of the field excitation of the generators driving the several motors.

NATHAN WILKINSON.
